UNITED STATES PATENT OFFICE

ALVIN H. SHOEMAKER, OF SEATTLE, WASHINGTON

DESIGN FOR A TIRE

Application filed December 29, 1931. Serial No. 42,278. Term of patent 7 years.

To all whom it may concern:

Be it known that I, ALVIN H. SHOEMAKER, a citizen of the United States, residing at Seattle, in the county of King and State of Washington, have invented a new, original, and ornamental Design for Tires, of which the following is a specification, reference being had to the accompanying drawing forming a part thereof.

In the drawing Figure 1 is a fragmentary

plan view of a tire embodying my design.

Fig. 2 is a fragmentary side elevation of the same.

Fig. 3 is a sectional view substantially on broken line 3—3 of Fig. 1.

Fig. 4 is a perspective view of a fragment of this tire.

I claim:

The ornamental design for a tire as shown.

ALVIN H. SHOEMAKER.
